KEY MEMBER TO PREVENT ACCIDENTAL RELEASE
OF A FLUORESCENT TUBE FROM ITS SOCKET

Filed March 6, 1951

UNITED STATES PATENT OFFICE

2,661,462

KEY MEMBER TO PREVENT ACCIDENTAL
RELEASE OF A FLUORESCENT TUBE FROM
ITS SOCKET

Lester J. Sklenar, Chicago, Ill., assignor to Illinois Tool Works, Chicago, Ill., a corporation of Illinois

Application March 6, 1951, Serial No. 214,180

4 Claims. (Cl. 339—54)

1

This invention relates generally to quickly operable fastening devices, and more particularly to a quickly operable fastener stud made of electrically non-conductive material and adapted to be mounted on fluorescent tube socket fixtures to prevent unauthorized or inadvertent removal of a mounted fluorescent tube therefrom.

The present invention is concerned with solving a problem which is primarily one of safety in the use of fluorescent tubes. It is not uncommon, because of vibration or other factors which are often present, to cause the release and precipitation of fluorescent tubes from their sockets, with the resultant possibility of damage to persons or property in the vicinity. This potential hazard is positively eliminated by the use of the safety key device, to which this invention is primarily directed, and this device is more fully described in later paragraphs. It is therefore an object of the present invention to provide a key or stud made of electrically non-conductive material which can be used in a majority of present types of installations to prevent unauthorized or inadvertent release of a fluorescent tube from its socket.

It is a further object of the present invention to provide a key or stud of the type described which includes means for retaining the stud in mounted position on the socket, said retaining means being releasable by an operator to enable withdrawal of the fastener and thereby permit removal of fluorescent tubes for replacement, inspection, etc.

It is still a further object of this invention to provide a one-piece stud fastener of the type described which may be very economically produced and which is designed so as to not detract from the appearance of present installations when used therewith, and further to enable the use thereof with many various sizes and designs of present commercial sockets.

It is still another object of the invention to provide a safety key or stud of the type heretofore mentioned having means thereon which indicates at a glance the relative position of the fastener to the socket, thereby assuring an inspector that the installation is secured and that the hazard of a falling light tube is not present.

The foregoing and other objects and advantages will be more apparent from the following detailed description when considered in connection with the accompanying drawings, wherein:

Fig. 1 is a perspective view of a fluorescent tube installation including the socket portion in which the tube is mounted, and shows the safety key mounted thereon;

2

Fig. 2 is a perspective view of one embodiment of the safety key contemplated by the present invention;

Fig. 3 is a plan view of one form of socket with the safety key ready for insertion therein;

Fig. 4 is a view of a fluorescent tube socket similar to Fig. 3 after insertion and rotation of the safety key to mounted position relative thereto;

Fig. 5 shows still another embodiment of safety key contemplated by the present invention;

Fig. 6 shows a plan view similar to Fig. 4 with the safety key of Fig. 5 mounted thereon and positioned to prevent inadvertent or unauthorized removal of the fluorescent tube from the socket member; and

Fig. 7 is a transverse sectional view taken along the line 7—7 of Fig. 4.

Referring now to the drawing more in detail, wherein like numerals have been employed to designate various parts throughout the several views, it will be seen that one embodiment of the present invention constitutes a safety key or fastener designated by the numeral 20. The safety key 20 is comprised of a shank portion 22 having a head 24 at one end thereof and a holding lug 26 axially spaced therefrom and extending radially outwardly from said shank. It is contemplated that the safety key 20, as shown in Fig. 2, will be fabricated of electrically non-conductive material, such for example as nylon, polystyrene or the like. This is necessary in view of the fact that the present safety key or fastener is so fabricated that when it is in mounted position the lug 26 is located in the vicinity of the electrical contacts within the fluorescent tube socket.

It will be seen by a study of the safety key device shown in Fig. 2 as well as other embodiments disclosed that the invention contemplates means in the form of a nub or protuberance 30 to prevent rotation of the fastener after it has been mounted on the socket member 28. The nub 30 coacts with the wall defining the entry port of the socket after rotation of the fastener relative thereto to retain the fastener in mounted position.

A study of Fig. 3 and the socket 28 disclosed therein leads to a more complete understanding of the usefulness of the present invention as well as to the operation of the safety key device. The socket 28 is composed of a body portion 32 with an entry port 34 opening into an annular recess or groove 36 which houses the prongs of a fluorescent tube. A contact arm 38 is located on each side of the port opening 34 and positioned within the confines of the annular recess 36. In the

disclosed socket a pair of shoulders or arms 40 are located between the aforementioned electrical contact arms and separated from each other by a slot 42 which is aligned with the entry port 34.

To mount a fluorescent tube in the disclosed sockets prongs 44 are aligned relative to the entry port 34, and the slot 42 between the shoulders 40 and moved axially through the entry port and into the annular recess 36. Thereafter the tube and prongs are rotated 90° during which rotation the contact arms 38 are sprung outwardly to position the prongs 44 therebetween. After said 90° rotation the tube is retained in this position due to the bowing of said contact arms 38 as clearly shown in Figs. 3 and 4. After attachment of the fluorescent tube to a pair of sockets 28 as hereinabove described, the entry port 34, which leads into the annular recess 36, is exposed and readily accessible for accommodating the safety key 20.

As will be seen in Fig. 3, the safety key is ready to be axially inserted through the entry port, and in Fig. 4 has been inserted and rotated 90° to position the holding lug 26 transverse to the entry port 34. It will be noted in Fig. 4 that the nub or protuberance 30 extends into the entry port or recess, and in this position retains the fastener against inadvertent or unauthorized rotation. The distance between the nub or protuberance and the nearest surface of the lug 26 may be slightly less than the thickness of the socket member 28 in the vicinity of the entry port. After insertion of the fastener into the entry port of the socket member, and during subsequent rotation to its mounted position, the head will be temporarily deflected as an incident to the engagement of the nubs or protuberances with the outer periphery of the socket member. These nubs 30 ultimately spring into interlocking association with the elongated entry port 34.

It should be noted that the nubs 30 are preferably rounded so as to present cam surfaces which permit an operator to remove the safety key with facility for replacement or repair of fluorescent tubes in the fixture.

As shown in the various figures a tab or wing head 48 extends axially from the shank 22 and the plane thereof extends normal to the longitudinal axis of the fluorescent tube when the fastener is in mounted position on the socket member. In this position the wing head 48 serves as an indicator to show from a distance that the tube is locked in position. Its primary uses are two-fold, first to facilitate turning of the key, and secondly, and of equal or greater importance, to serve as an indicator to disclose to an operator whether or not the lug 26 of the fastener is properly positioned to prevent removal of the tube from the socket. This indicator or knob may be highly colored so as to render it easily discernible by an operator for inspection purposes. It should be of sufficient size and shape to enhance the visibility thereof.

In Fig. 5 a modified form of the instant invention is disclosed, wherein the head of the fastener has its opposed margins deflected toward the lug holding means so that said margins are spaced from the lug holding means a distance less than the thickness of the material of the socket member with which it is to be used. In the embodiment disclosed in Fig. 5 the fastener head 24a is formed arcuately so as to position the opposite margins 30a thereof toward the clamping side of the lug 26a. It will be noted also that the corners of these margins are rounded so as to facilitate application. The arc of the head

24a is formed on a shorter radius than the arc presented by the complementary surface of the socket 28. Thus, when the fastener or key 20a is applied to the socket in the manner previously described in connection with the fastener 20, the opposite margins 30a of the head are sprung sufficiently to permit complete insertion of the lug 26a. After the key has been turned so as to position the wing head or knob 48a transversely of the elongated opening for accommodating the head 26a, as shown in Fig. 6, the resilient margins 30a of the head 24a resiliently bear against the complementary periphery of the socket 28. This frictional engagement is sufficient to prevent unauthorized removal or loosening of the key 20a. By employing the resilient head structure 24a, the necessity for using the locking lugs 30 of the fastener 20 is eliminated.

It should also be pointed out that the head 24 previously described, when occupying its locked position as shown in Figs. 1, 4 and 7, serves as an abutment for the fluorescent tube 50. In installations where the socket members are spaced a distance which will permit of some axial shifting of the fluorescent tube, the extremity of the heads 24 projecting beyond the inner surface of the depending portion of the socket 28, as clearly shown in Fig. 7, serves to limit the extent to which this axial shifting of the fluorescent tube can take place. Hence, the danger of loosely fitted fluorescent tubes is reduced to a minimum.

While for purposes of illustration a particular commercial form of socket has been shown, it will be apparent that the invention is applicable for use with other forms of socket members. For example, some commercial forms of socket members are equipped with two entry ports to permit mounting of the tube, and in such cases the safety key or fastener is usable. It will be understood that the invention is capable of other modifications and changes from those disclosed in the drawing without departing from the scope of the appended claims.

The invention is hereby described as follows:

1. A one-piece quickly operable safety key for use with fluorescent light socket fixtures and made of a dielectric material, said key including a shank, a resilient head at one end thereof, finger gripping means associated with said head to facilitate rotation of said shank, an elongated holding lug spaced axially from said head and extending radially outwardly in opposite directions from said shank, and means on the under surface of said head extending in a direction toward said holding lug adapted to engage a complementary light socket fixture so as to resist rotation of said key when mounted in locking position on said socket, said resilient head and said elongated holding lug coacting to clampingly engage opposed surfaces of a complementary socket fixture.

2. A one-piece quickly operable safety key as set forth in claim 1, wherein the finger gripping means associated with the head comprises a substantially flat plate-like section containing the axis of said shank and adapted to be gripped by the fingers.

3. A one-piece quickly operable safety key as set forth in claim 1, wherein the means on the under surface of said resilient head consist of deforming opposite free extremities of said head portion in the direction of said holding lug adapted to engage a complementary surface of a light socket fixture to resist rotation of said key when mounted in locking position on said socket.

4. A one-piece quickly operable safety key as set forth in claim 1, wherein locking lugs are provided on the under surface of the resilient head of said key which extend in a direction toward said holding lugs and are adapted to engage a complementary light socket fixture so as to resist rotation of said key when mounted in locking position on said socket.

LESTER J. SKLENAR.
